POWDER CONTAINER DISPENSING HEAD

Harry A. Ciufi, San Francisco, Calif.

Application July 21, 1936, Serial No. 91,688

13 Claims. (Cl. 221—66)

This invention relates to powder-dispensing devices generally and more specifically to a powder container dispensing head and closure for containers for tooth powder, abrasive powders, or other powders, and has for its objects the provision of a dispensing head or cap that will seal the contents of the container against discharge through the head when not in use and will also permit opening the head to flow of powder therethrough and will insure a free flow of the powder at all times when the head is open to flow. Other objects and advantages will appear in the specification and drawings annexed hereto.

15 In the drawing, Fig. 1 is an elevational view of my device on the upper end of a container.

Fig. 2 is a sectional view as seen from the line 2—2 of Fig. 1.

Fig. 3 is a top plan view of my device with the head closed to flow of powder.

Fig. 4 is a plan view with the head open to flow of powder.

Fig. 5 is an enlarged perspective view of a portion of the working mechanism within the head.

25 Fig. 6 is a sectional view as seen from the line 6—6 of Fig. 3 with the head inverted, the portion of the container being shown with the head attached.

In detail, my invention comprises a cap-like shell formed with a cylindrical skirt 1 adapted to be secured to the neck of a container 2 by crimping, threading, soldering, or by friction, as may be desired, the figures in the drawing showing the shell firmly held in place by friction so as to be removable, if desired, but which will not be accidentally dislodged. The walls of the shell are convergently tapered from the skirt portion to a horizontally elongated discharge aperture 3 in axial alignment over the opening in the neck of the container 2, said walls at two opposite sides 5 being flat and of greater inclination relative to vertical and terminating at their outer edges adjacent the longitudinal edges of the aperture 3 while the two opposite walls 6 at right angles to walls 5 are more nearly vertical and terminate at their outer edges adjacent the ends of aperture 3. All four sides 5, 6, 6, are slanted toward the aperture 3 to their outer margins along the aperture 3, which opposite margins of opposite walls are turned toward each other to almost horizontal, but still slightly inclined toward the aperture so as to insure the powder in the container being directed toward the single aperture when the container is inverted as in Fig. 6.

Removably covering the aperture 3 is an elongated resilient strip of metal 7 turned up at its opposite ends at 8 so the strip will conform longitudinally and transversely to the shape of the margins of the walls 5, 6 at the aperture and will overlap the margins at the side edges of the strip and extend across the aperture 3, while the ends 8 will lie alongside and against the side walls 6. Said ends 8 are struck inwardly slightly at 9 to form relatively small inwardly projecting bosses and the side walls 6 are correspondingly struck inwardly to form sockets to rotatably receive the bosses so the bosses will snap into the sockets for pivotally securing the strip in place on the shell in a position to swing laterally to cover and to uncover the aperture 3. The ends 8, being resilient, will frictionally grip the walls 6 sufficient to hold the strip in open or closed position relative to the aperture, but will permit the strip to easily be moved to either position.

The shell comprising the main body of the head is annularly grooved at 10 adjacent the juncture of the skirt 1 and sides 5, 6, for providing means for holding a mechanism within the head for loosening the powder and moving the strip 7 from over the opening.

This mechanism comprises a spring wire (see Figs. 2, 5 and 6) bent to substantially annular form at one end to form a ring position 11 which ring is adapted to be sprung into place within the groove 10 within the shell. This wire is then bent to extend slantingly away from the plane of the ring toward the axis of the ring at 12 and is formed with a loop 13 positioned about 30 at the axis of the ring from which loop the wire is extended at 14 toward and to adjacent one end of aperture 3 where it is turned back again at 15 to extend alongside and adjacent one of the walls 5 to about the plane of the ring 11 35 where it is bent to extend horizontally across the shell to the opposite wall 5, at 16, then down along the inner side of wall 5, at 17, and through the aperture 3 at the end thereof. The end of the wire projecting through the aperture 40 is bent at 18 transversely of the aperture so as to slightly overlie the margin of the wall at the aperture. At a point about intermediate the ends of the portion 14 of the wire, said portion is formed with a small loop 19 through which is 45 projected one end 20 of a horizontal wire 21, the end 20 being bent beyond the loop slightly so as to prevent its withdrawal from the loop. This wire 21 passes fairly loosely through a small 50 aperture 22 in a side wall 6 to outside the shell 55

where it is extended outwardly a distance and formed at its outer end to a ring 23 that is disposed in a plane parallel to the longitudinal axis of the shell.

5 The wire 21 extends in a direction transversely of the plane in which portions 15, 17 of the wire mechanism within the shell are disposed and extends through the side wall 6 of the shell adjacent the end of aperture 3 in which the portion 18 is disposed so that upon pressing against ring 23 the end 18 will be moved against the force of spring loop 13 to the opposite end of the aperture 3 and the portions 15, 17 will also move over the side walls 5. Upon releasing pressure on ring 23 the end 18 and portions 15, 17 will automatically swing back to normal position again under the influence of spring loop 13.

One of the longitudinally extending edges of the strip 7 that normally covers the aperture 3 is notched at one end 7' to pass the end of the wire adjacent the bent end 18 thereof with the inclined side of the notch extending toward the end of the aperture opposite the end thereof at which end 18 is normally positioned, thereby providing a cam surface so that the movement of the end of the wire projecting through the aperture 3 will automatically force the strip 7 to uncover the slot, as seen in Fig. 4, upon pressing ring 23, and at the same time loosen the powder in the shell to flow through the aperture and the portions 15, 17 of the wire will also move at the same time to prevent packing of the powder on the sides of the shell. After the first full operation on ring 23 to effect a full swing of end 18 from end to end of the aperture, merely an alternate pressure and release of the finger on ring 23 will cause a continuous flowing of powder (when the container is inverted) without any possibility of the powder packing at the aperture and arching inside the shell. After the desired amount of powder has been discharged, the operator merely swings the strip 7 across the aperture to closed position, the end 18 forming a stop, and the container closed.

45 It will be seen from the foregoing that a cheap, highly efficient, and positive construction is provided to insure a free flow of powder from a container and to close the container when not in use. There are no soldered joints, and only four parts 50 to the entire head, all of which can be cheaply made and assembled.

While I have shown a metal container 2, it is obvious that the container can be of any material, such as glass, cardboard, "Bakelite", or the 55 like. Likewise the material of the shell can be hard rubber, "Bakelite", etc.

From this detailed description and illustration of one preferred embodiment, the invention itself, in its broader aspects, will be clear to those 60 skilled in the art.

It might be added that adjacent aperture 3 the portions 15, 14, of the wire extend transversely across the aperture as at 25 and I have found that this portion 25 also materially assists in 65 insuring free flow of powder, and although I have found that the provision of projection 18 is preferable, nevertheless very good results are obtainable by omitting the same, also I have found that I can obtain good results by omitting portions 70 15, 17, and forming the wire 14 at its outer end with a projection similar to the end 18.

Having described my invention, I claim:

1. A device for delivering powdered material from a container comprising a hollow body open 75 at one side for admitting material to within

the body and the body being formed with an elongated discharge aperture for discharging the material therefrom, a member disposed normally at one end of said aperture mounted for oscillatory movement in opposite directions substantially from end to end of the aperture, means for moving said member, said member being formed to permit a substantial flow of material through the aperture to substantially the full flow capacity of the aperture at all times during movement of said member and to break up the powder against packing at the aperture upon its movement. 5

2. In a construction as defined in claim 1, the walls of said body being convergently tapered 15 toward the edges of the aperture, and said member projecting from within the aperture therethrough and terminating adjacent the outer side of the body at the aperture.

3. In a construction as defined in claim 1, a 20 closure on said body movable from a position covering said aperture to a position uncovering said aperture, automatically actuated by said member upon movement thereof from its normal position at one end of the aperture to the opposite end for moving the closure to the position uncovering the aperture. 25

4. In a construction as defined in claim 1, means within said member extending away from the aperture and adjacent the inner sides of 30 the body connected to said member for simultaneous movement therewith for dislodging material disposed along the inner sides of the body and for facilitating the flow of material along the sides toward the aperture. 35

5. In a device of the character described, a container for powdered material provided with a dispensing head for dispensing said material therefrom, said head comprising a tubular body opening at one end to within the container and 40 the opposite end being formed with an elongated discharge aperture, a movable member projecting through the aperture in a normal position at one end thereof, spring means arranged and adapted to yieldably urge said member to said 45 normal position at one end of said aperture, means accessible for pressing by a finger of a person arranged and adapted to move said member to the opposite end of said aperture against the force of said spring means upon pressure of the finger being applied thereto and said spring means being operative to automatically return said member to its normal position upon relieving said pressure, a closure movably mounted on said head normally covering said aperture before actuation of the means for moving said member arranged and adapted to automatically be moved to a position uncovering said aperture by movement of said member to said opposite end of the aperture and to remain in said position upon 50 return of said member to its normal position. 55

6. In a construction as defined in claim 5, said closure being arranged and adapted for manually returning the same to a position covering said aperture only when said member is in said 65 normal position.

7. In a construction as defined in claim 5, said spring means comprising a spring wire and said member being a continuation of said wire.

8. In a construction as defined in claim 5, two 70 opposite side walls of said tubular body extending divergently from the opposite elongated edges of said aperture in a direction toward said container whereby the material will be directed toward said aperture for discharge therefrom. 75

9. In a device of the character described, a container for powdered material provided with a dispensing head for dispensing said material therefrom, said head comprising a tubular body opening at one end to within the container and the opposite end being formed with an elongated aperture, one of the side walls of said body being flattened and extending slantingly from one of the elongated side edges of said aperture relative 5 to the side wall opposite thereto toward said container, means within said body positioned adjacent said flattened side wall mounted for movement along said flattened side wall in a direction longitudinally of said aperture for loosening 10 powdered material in said body, and manually actuated means accessible from outside said body for manually causing said movement in one direction.

10. In a construction as defined in claim 9, 20 spring means connected to said first-mentioned means for causing said first-mentioned means to move in the opposite direction upon release of the manually actuated means.

11. In a construction as defined in claim 9, a 25 member secured to said first-mentioned means and movable therewith projecting into said aperture, and spring means yieldably retaining said first-mentioned means in a position at one side of said body.

30 12. In a device of the character described, a con-

tainer for powdered material provided with a dispensing head for dispensing said material therefrom, said head comprising a tubular body opening at one end to within the container and the opposite end being formed with an elongated aperture, two opposite side walls of said body being flattened and extending divergently from the opposite elongated side edges of said aperture toward said container, a pair of elongated elements positioned within the body extending respectively from said aperture along said side walls in a direction toward said container and substantially parallel to said side walls, and means for moving said elements longitudinally of said aperture in opposite directions for loosening powder at the aperture and along said side walls to prevent packing of the powder within the head, and means mounting said element for said movement.

13. In a construction as defined in claim 10, one 20 of said elements having an extension at its end adjacent said aperture extending transversely across said aperture, said extension being movable with said element and of small dimensions relative to the area of said aperture whereby 25 there is substantially no obstruction to flow of material through said aperture during its movement with the element to which it is connected.
